United States Patent Office.

GEORGE RUPPEL, OF HARLEM, NEW YORK.

Letters Patent No. 73,841, dated January 28, 1868.

IMPROVEMENT IN TRUNK-LOCKS.

The Schedule referred to in these Letters Patent and making part of the same.

TO ALL WHOM IT MAY CONCERN:

Be it known that I, GEORGE RUPPEL, of Harlem, in the county and State of New York, have invented a new and improved Trunk-Lock; and I do hereby declare that the following is a full, clear, and exact description thereof, which will enable those skilled in the art to make and use the same, reference being had to the accompanying drawings, forming part of this specification, in which—

Figure 1 represents a rear view of my improved lock.

Figure 2 is a rear view of the removable portion of the same.

Figure 3 is a rear view of the removable portion, the outer or back cover being removed.

Figure 4 is an inner or front view of the stationary portion of my improved lock.

Figure 5 is a vertical central section of the lock, the plane of section being indicated by the line $z z$, fig. 1. Similar letters of reference indicate corresponding parts.

This invention relates to a new kind of lock, which is intended to be used on trunks, satchels, carpet-bags, and wherever a folding lid is to be locked to a stationary or also folding body.

The invention consists in the use of a removable circular lock, which is to be connected with a circular plate, that is attached to the stationary part of the trunk, said lock having a central bolt, which, when inserted through an oblong hole in the aforesaid plate, and then through one in a plate attached to the cover, will securely connect the two parts of the trunk or bag, and also the lock to the same, after the lock is turned one-quarter around. The bolts, which are arranged in the lock, are, by means of suitable springs, thrown into holes provided in a flange projecting from and around the circular plate, said flange lapping over and around the lock, and the main or central bolt has a T-shaped head, which is passed through the oblong slot in the plate, and which, when the lock is turned, secures the lock to the plate. Another similar head, at the further end of the central bolt, secures, in a similar manner, the lid to the body of the trunk or bag. To remove the lock and open the trunk, the small bolts must be pushed out of the recesses in the plate by means of a key having pins, the latter fitting through holes arranged in the rim of the lock. These pins, if not of the exactly correct length, will either not be long enough to push the bolts out, or they will be too long, and will push the bolts into recesses provided in the flange of the plate, at the opposite side, which arrangement is easily obtained by the circular form of the lock. When the bolts are pushed out of the flange, the lock can be turned until the head of the central bolt is in line with the slot in the plate, and the lock can then be taken off, and the trunk or bag is open.

A represents a circular metal plate, secured by means of screws, or otherwise, to the body or lid of a trunk or carpet-bag. It has in its centre an oblong slot, a , as is clearly seen in figs. 1 and 4, and is, at or near its circumference, provided with a flange, b , which projects towards the front, as shown, (fig. 5.) B is a circular cup, or a round plate with a flange around it, the inner diameter of which is equal to the outer diameter of the flange b . If desired, the outer diameter of the flange on B may be made equal to the inner diameter of the flange b . In the centre of the cup B is a stem or central bolt, C, which has a T-shaped head, c , which, when the two parts A and B are brought together, will fit through the slot a , and when, then, the part B is turned, it will stand as in fig. 1, and will connect the parts together. Within the cup B are arranged three or more or less bolts, D D, which are arranged parallel with one diameter of the cup, and all parallel with each other, all being as long as the distance in the flange b of those points which are touched by the bolts. By means of spiral or other suitable springs, $d d$, which are guided in suitable grooves in the cup, the bolts D are thrown towards the flange of the cup B. Each of these bolts, D, has a lip, e , which, as is seen in fig. 5, is under one of a number of small holes, f , that are arranged in the rim of the cup, the lip being near that end of each bolt which is thrown out by the spring.

It will be clearly understood that, when the cup or lock B is detached, the ends of the bolts D are, by the springs d , thrown against the inner side of the flange of the cup. To fit the cup to the plate A, its flange must first be cleared from the bolts, so that it can be fitted over the flange b . For this purpose, a key, E, having as many pins, g , as there are bolts and holes, f , is applied to the cup. The pins g are fitted through the holes f , so that they touch the lips e , and the key is then pressed in so as to push the bolts back towards the opposite side. The cup can now be attached to the plate A, and the key removed. The cup is then turned until the

ends of the bolts D are forced by the spring d into holes, h h, provided in the flange b, as is clearly shown in fig. 4. At the same time, the two parts A and B are also connected by the central bolt C. The same may, at its extreme end, have another head, which fits through an oblong slot, provided in the lid or opposite part of the trunk or bag, as is indicated by red and blue lines in fig. 5, or the head e may be fitted directly through the slot in the plate A, and through that in the lid. Opposite to the holes h, are holes i, arranged in the flange b for the purpose of receiving the other ends of the bolts, in case it is attempted to open the lock with a false key, so that when the pins on such a false key are too long, the bolts may be pushed into the holes i, as will be understood from fig. 5.

For unlocking, the bolts D must be cleared from the flange b by means of the key E, and the cup B turned until the head e is in line with the slot a, which is ascertained by means of a stop, j, arranged on the plate A, said stop also preventing the turning of the cup when locked. The cup can then be taken off, and the trunk or bag will be open, and cannot be locked again without the use of the cup.

It will be observed that a key-hole and a lining for the same are not needed where this lock is used, which is a great saving in the cost of construction of trunks, satchels, &c. The lock can be made of suitable dimensions, and can, on account of its simplicity, be made very small and light.

If desired, the head, e, of the bolt may be dispensed with, especially if such a head is already on the outer end of the bolt to connect the lid to the trunk. The invention can also be used on doors and other places to protect and cover the key-holes.

I claim as new, and desire to secure by Letters Patent—

The manner, herein shown and described, of attaching the cup B to the plate A, and to the two parts of the trunk or bag, by means of sliding-bolts D D, and a central-headed stem, C, all made and operating substantially as herein shown and described.

GEORGE RUPPEL.
